Inventor:
Joseph B. Strauss
By Parker & Carter, Atty.

UNITED STATES PATENT OFFICE.

JOSEPH B. STRAUSS, OF CHICAGO, ILLINOIS.

BRIDGE.

Application filed March 1, 1926. Serial No. 91,441.

This invention relates to movable bridges and has for its object to provide a new and improved device of this description.

The invention has as a further object to provide an artistic movable bridge.

The invention has as a further object to provide a movable bridge having an operator's house which is normally concealed or out of the way so as not to interfere with the artistic effect of the bridge and which can be moved to an operative position where the operator will have a proper view of the bridge while it is being opened and closed.

The invention has other objects which are more particularly pointed out in the accompanying description.

Referring now to the drawings:

Fig. 1 is a view in part section of one form of bridge embodying the invention with the operator's house in its concealed position.

Fig. 2 is a view similar to Fig. 1 with parts broken away showing the operator's house in its raised or operative position, and the bridge span also raised.

Fig. 3 is a sectional view taken on line 3-3 of Fig. 1.

Fig. 4 is a sectional view taken on line 4-4 of Fig. 1.

Like numerals refer to like parts throughout the several figures.

Referring now to the drawings, I have shown one form of movable bridge, namely a bascule bridge having a movable leaf 1 mounted upon trunnions 2. The leaf is shown as provided with an ornamental railing 3 which may be of any suitable form. Any other desired ornamentation or artistic effect may be added to the bridge. The movable leaf 1 is provided with a counterweight 4 connected to the tail end thereof. In the construction shown this counterweight is pivotally connected by the pivot 5 with the tail end of the leaf. The trunnions 2 are carried by the supports 6. The movable leaf is provided with suitable mechanism for raising and lowering it.

The operator's house 7 is provided for the operator who operates the controlling machinery. When the leaf is being raised or lowered it is necessary for the operator to be in a position where he can see the end of the movable leaf and also have a view of the water on opposite sides thereof so that he can know when to open the leaf and when to close it, and so that he can operate this

movable leaf without injury to people on the bridge or approaching the same, or to vessels passing the bridge. This means that the operator's house must, when the bridge is being operated, project above the floor of the bridge to give the operator the proper view. When an ornamental bridge is provided this operator's house if permanently projecting above the floor of the bridge, may mar the symmetry or artistic effect thereof and in order to prevent this I have provided an operator's house arranged so that it can be raised when it is desired to operate the bridge in order to give the operator the proper view, and lowered when the bridge is closed so as not to interfere with the artistic effect.

In the drawings I have illustrated one form of apparatus for this purpose. In this construction there is a pit 8 at one side of the movable leaf. This pit contains mechanism for raising and lowering the operator's house 7. In the construction shown the operator's house 7 is provided with racks 9 and 10. The rack 9 is engaged by gear 11 connected with a shaft 12 and the rack 10 is engaged by a gear 13 connected with a shaft 14. The gear 12 also engages a rack 15 on a counterweight 20 which is free to move in a guiding device 21. The gear 13 engages a rack 22 on a counterweight 23 which is free to move in a guiding device 24. When the gears 12 and 13 are rotated in one direction the operator's house 7 is moved up to the position illustrated in Fig. 2 and when these gears are moved in the opposite direction the operator's house is moved down into the pit 8 as illustrated in Fig. 1. During this movement the operator's house is counterbalanced by the counterweights 20 and 23. The racks 9 and 10 are preferably located near the middle of the operator's house and project downwardly and are connected together at the bottom by the connecting piece 25. There are also braces 26 extending from the bottom of the racks upwardly and connecting with the operator's house.

Some means is provided for gradually stopping the operator's house when it is lowered. In the construction shown there are cylinders 27 and 28 preferably containing some resisting liquid and provided with pistons which are connected to rods 27^a and 28^a. These rods engage a fixed part when

the operator's house nears the limit of its downward movement and cause the pistons to move in the cylinders, the fluid therein resisting this movement and gradually stopping the operator's house without a jarring effect.

Some suitable source of power is provided for operating the raising and lowering mechanism for the operator's house. I have shown a device for this purpose consisting of an electric motor 29 which is connected through the speed reducer 30 to the shaft 31. This shaft, by means of bevel gears 32 and 33, drives the shaft 34. The shaft 34 is connected by bevel gears 35 and 36 with the shaft 12 of the gear 11 and by the bevel gears 37 and 38 with the shaft 14 of the gear 13. The shaft 12 is mounted in suitable bearings on supports 39 and 40, and the shaft 14 is mounted in suitable bearings on supports 40 and 41. The shaft 34 is mounted in suitable bearings on the support 40.

The bridge is opened and closed by means of a motor, not shown, which drives the pinion 48 on the shaft 47. This pinion engages the rack 49 on the movable leaf 1. The motor is controlled from the operator's house through the agency of the electrical cable 50 which leads to the operator's house and which has the loop 51 to permit the raising and lowering of the operator's house.

The operator's house is provided with a switch board 52 (see Fig. 4) for the controlling mechanism for the motor. The motor 29 for the operator's house is also controlled from this switch board by means of the conductor 53 which branches off from the cable 50.

The operator's house is provided with a door 7^a and when the house is in the pit, access thereto is provided by means of the ladder 54.

It will be seen that by means of this device the operator's house may be easily and quickly raised so that the operator will have a clear view when it is desired to operate the

bridge, and that it can be easily and quickly lowered so as to be out of the way when the bridge is not being operated.

I claim:

1. A bridge comprising a movable leaf, electrically controlled operating mechanism for opening said leaf, an operator's house containing the control apparatus for said operating mechanism, and means for raising said operator's house when it is desired to open said leaf so that the operator has a full view of said leaf, and for lowering said house when the bridge is closed so that the house will be out of sight.

2. A bridge comprising a movable leaf, operating mechanism therefor, an operator's house out of alignment with said leaf, a pit into which said operator's house is adapted to be received, and means for raising said operator's house out of said pit so that it projects above the roadway when it is desired to open said leaf.

3. A bridge comprising a movable leaf, operating mechanism therefor, an operator's house out of alignment with said leaf, a pit into which said operator's house is adapted to be received, racks connected with said operator's house, pinions connected with said racks, and means for driving said pinions so as to raise said house to a position where the operator has a view of said leaf.

4. A bridge comprising a movable leaf, electrically operated mechanism for opening said leaf, an operator's house containing the control apparatus for said operating mechanism, means for raising said operator's house when it is desired to open said leaf so that the operator has a full view thereof, and for lowering said house when the bridge is closed so that the house will be out of sight, and flexible connections between said operating mechanism and said operator's house.

Signed at Chicago county of Cook and State of Illinois, this 23rd day of February, 1926.

JOSEPH B. STRAUSS.
